Mr. 587
 Robert H. St. Peter & Co., Inc., have as Patents
 Design for a Cooking Range
 Patented September 1853.

May 587

Reuben H. N. Bates, of Providence, R. I.

Assignor to

North, Chase & North, of Philadelphia, Pa.

Letters Patent No. 587. Dated July 26th 1853.

.....

The schedule referred to in these Letters Patent and making part of the same

.....

To all whom it may concern:

Be it known that I, Reuben H. N. Bates, of the City and County of Providence, and State of Rhode Island, have invented a new and ornamental design for a cooking range; and I do hereby declare that the following is a full and exact description thereof, reference being had to the accompanying drawings, and to the letters of reference marked thereon —

Fig 1. represents a plate at the side of the fire chamber.

Fig 2. represents a plate forming one of the oven doors.

Fig 3. represents a door to the fire chamber.

Fig 4. represents a broiling door.

a, is an ornament formed by a diamond, placed in the center of a bundle of arcs edges, some of which are straight & others more or less curved. It is the center ornament of a panel, at the corners of which are bundles of reeds, b, springing from an arc, and the whole is surrounded by an ornament, formed of drops, c, enclosed in curved scrolls.

d, d—e, is an ornament formed by an oblong diamond with spear points. It is placed in the center of a panel, & surrounded by drop & scroll work f f—g, is an ornament similar to e, placed between two spear points h, h, which spring from the point of contact of the scrolls i, i.—m, is an ornament similar to e, except that the diamond in the center
